UNITED STATES PATENT OFFICE.

ROBERT J. MAGOR, OF PASSAIC, NEW JERSEY.

BOX-CAR.

1,080,708.

Specification of Letters Patent.

Patented Dec. 9, 1913.

Application filed July 10, 1911. Serial No. 637,673.

To all whom it may concern:

Be it known that I, ROBERT J. MAGOR, a subject of the King of Great Britain, and a resident of the city of Passaic, in the State 5 of New Jersey, have invented an Improvement in Box-Cars, of which the following description, in connection with the accompanying drawings, is a specification, like letters on the drawings representing like parts. 10 The object of the improvements is to provide a box-car body which shall be collapsible, that is one in which the roof, sides and ends may be detached from each other in such a way as to be capable of being laid 15 flatwise upon the floor or underframe of the car for purposes of shipping.

Referring to the drawings, Figure 1 is a view in side elevation of a box-car embodying the improvements, the view being partly 20 broken away for purposes of clearer illustration. Fig. 2 is a similar view in end elevation. Fig. 3 is a view in end elevation with the roof, sides, and end detached from the 25 floor and underframe of the car, and, Fig. 4 is a detailed view of the top portion of an end showing a modification.

The car shown in the drawings belongs to that class of box-cars, now well-known and in common use, having a single sheathing 30 along its sides and ends provided with an exterior bracing. In the case of the present drawings this sheathing consists of boards *a* laid one over the other and dove-tailing as shown in Figs. 2 and 3, tightening means being 35 preferably provided to unite said sheathing boards together and permit of their being disassembled and replaced when necessary. These tightening means may consist of rods *b* provided with nuts *c*, the lower 40 ends of the rods as shown extending down through the flanges in the side and end channels respectively of the underframe *d*. The assembling of the sheathing boards to form a side or an end will be so easily understood 45 from Figs. 2 and 3 as to require no further description here, this forming no part of the present invention. When fully assembled, a bolt may be passed through the sheathing board into the exterior bracing irons *e*, or 50 several of the same, around the car. In addition to the irons *e* which are vertical it may be noted that bracing irons *f* are preferably to be provided at convenient places along the sides of the car.

55 The roof of the car has a frame which is

formed of two longitudinal irons *g*, shown in Figs. 2 and 3 as being angle-irons, and transverse irons *h* upwardly arched toward the center and upon which the longitudinal wooden beams *i* rest which support the roof 60 proper *k*. In the present drawings, the transverse members *h* at the ends are angles, while the intermediate transverse members *h*, as indicated in Fig. 1 are T-irons. These shapes are not particularly essential, but it is 65 preferable that the transverse irons shall have a horizontal flange to present a flat support for the beams *i* and a vertical web to impart the proper strength. The longitudinal members *g* have their horizontal 70 flanges turned inward and their vertical flanges pointing downward. Coöperating with these vertical flanges of the longitudinals *g* are the vertical flanges of another pair of longitudinal angles *l* along 75 the tops of the car sides, said longitudinal angles *l* being preferably secured to the exterior irons *e* along the sides of the car. The horizontal flanges of the angles *l* are turned outwardly and the vertical 80 flanges point upwardly; and these latter when the sides and roof are in position on the car abut against the vertical flanges of the corresponding angles *g*, being secured thereto along the side of the car by bolts *m* 85 (Fig. 2). Thus, when the sides and roof are separated, the flanges *l* and *g* serve as strong framing or brace members for the sides and roof respectively and tend to prevent their 90 injury or distortion during transit.

The modification shown in Fig. 4 consists in making the angles *l* and *g* in one integral piece denoted by *n*. In such a case, upon disassembling, it will be preferable to allow the longitudinal *n* to remain attached to the roof, 95 and to detach them from the side irons. It will be observed that in either case, the angles *l* and *g*, or the single longitudinal *n*, presents the form of a letter *Z* the upper flange of which points inwardly and the 100 lower flange of which points outwardly, while the intermediate flanges or portion are substantially vertical.

In collapsing the car, the nuts *c* are removed as well as the bolts *o* which unite the exterior irons *e* and *f* to the underframe thus 105 releasing the superstructure from the floor or underframe of the car. Then, or at the same time, the bolts *m* are removed to disconnect the roof from the sides. It will thus 110

be seen that the operation of taking the car body apart, or the converse operation of putting it together, are very simple indeed.

I claim as my invention:

- 5 1. A collapsible box car superstructure having an iron secured along each edge of the roof to serve as a frame member to prevent injury and distortion to the roof while detached, and an iron secured along the top of each side serving a similar purpose while the sides are detached, the two irons on the same side of the car fitting together when the roof and sides are in position, and means to unite said two irons on each side when the car is assembled.
- 10 2. A collapsible box car superstructure having an angle-plate along each edge of the roof with its horizontal flange directed inwardly and its other flange directed down-

wardly, said angle-plate being secured to the roof to serve as a frame member to prevent injury and distortion to the roof while detached, and an angle-plate along the top of each side with its horizontal flange directed outwardly and its other flange directed upwardly, said second angle-plate serving as a frame member for the corresponding side while detached, and means to unite the upwardly and downwardly projecting flanges on each side when the car is assembled.

In testimony whereof, I have signed my name to this specification, in the presence of two subscribing witnesses.

ROBERT J. MAGOR.
